UNITED STATES PATENT OFFICE.

MELVIN BURRIS, OF MENDON, OHIO.

FENCE-POST MOLD.

1,147,075.

Specification of Letters Patent. Patented July 20, 1915.

Application filed November 21, 1914. Serial No. 873,339.

To all whom it may concern:

Be it known that I, MELVIN BURRIS, a citizen of the United States, residing at Mendon, in the county of Mercer and State of Ohio, have invented certain new and useful Improvements in Fence-Post Molds, of which the following is a specification, reference being had to the accompanying drawings.

10 My invention relates to molds for forming articles from concrete or like artificial stone, and particularly to molds for forming the intermediate and corner posts of fences.

The main object of my invention is the 15 provision of a very simple mold for forming a concrete fence post so constructed as to form an integral brace on the post extending either in one or two directions from the post.

20 A further object is to provide a mold of this character which shall be simple in construction and formed of sections so connected as to be readily taken apart and put together.

25 Still another object of the invention is to provide a mold which is adapted to rest upon the ground and to form the upper part of a fence post, the lower part having been already formed by pouring concrete 30 into a suitable trench cut into the ground.

Still another object of the invention is to provide means whereby the interior strips used for forming the inner walls of the mold shall be readily removed when the 35 mold is taken apart.

Still another object of the invention is to so construct the mold that the sections may be taken apart without the necessity of hammering the bolts holding the sections together or dislodging the mold strips by force 40 so as to prevent any chance of breaking the concrete forming the post.

Other objects will appear in the course of the following description.

45 My invention is illustrated in the accompanying drawings, wherein—

Figure 1 is a side elevation of one form of my fence post; Fig. 2 is a perspective view of another form of post; Fig. 3 is a side elevation of the mold used for the form of post shown in Fig. 1; Fig. 4 is a vertical section through the post shown in Fig. 1 with the mold in place; Fig. 5 is a section on the line 5—5 of Fig. 3; Fig. 6 is a section on the line 6—6 of Fig. 4; Fig. 7 is a section on the line 7—7 of Fig. 4; Figs. 8

and 9 are perspective views of the cover plates; Fig. 10 is a horizontal section taken through the mold used for forming the fence shown in Fig. 2.

Corresponding and like parts are referred to in the following description and designated in all parts of the accompanying drawings by like reference numerals.

These figures illustrate a concrete fence post, Fig. 1 illustrating one of the intermediate posts of the fence, and Fig. 2 one of the corner posts of the fence. It will be seen that each post comprises an upwardly extending shaft *a* whose lower end is sunk sufficiently deeply into the ground, and which extends above the ground, and formed integral with the post *a* is a brace *b* or a plurality of these braces, as in Fig. 2, that extend downward and outward a suitable 75 distance from the base *a*, and connected to the base *a* by a transverse member *c* resting on the ground and preferably disposed in a trench formed in the ground. The lower portion *a*^x of the post and the member *c* are 80 first formed by cutting a suitable vertical hole in the ground from which extends a trench disposed at the ground level. The concrete is then poured in this L-shaped recess in the ground so formed, and afterward 85 the upper portion of the post is formed upon the basic portion by means of the mold which will be hereinafter described. The only difference between the form shown in Fig. 1 and that shown in Fig. 2 is that in 90 the latter two braces *b* are used and two connecting members *c*.

As before stated, the mold is adapted to be set upon the ground on each side of the connecting member *c* and while the concrete 95 or artificial stone of this connecting member is still soft, and to this end the mold consists of two sections. Where the fence post shown in Fig. 1 is to be formed, each section is triangular in general form and consists of 100 a plate 2 of relatively thin sheet metal. The rear portion of this plate forming the vertical side of the triangle is curved as at 3 to constitute the curvature of the post *a*. The base of the triangular plate 2 is provided with outwardly extending feet 4 and 4^a which are formed of angular strips riveted to the plate 2. The upper portion of the strip forming the foot 4^a is outwardly bent as at 5 and extends above the upper 110 edge of the mold plate 2, and is longitudinally slotted as at 6. Attached to the upper

margin of the plate 2 adjacent the curved portion 3 and projecting above the upper edge of the plate 2 is an ear 7 which above the rivet 8 is slightly deflected, the upper 5 end extending above the upper edge of the plate 2 and being formed with the longitudinal slot 9 extending in the same direction as the slot 6. Midway between the upper ends of the members 4^a and 7 is disposed an out- 10 wardly projecting ear 10 formed by riveting an angular piece of metal to the upper margin of the plate 2. In order to form the fence post shown in Fig. 1 there are two of these plates 2, both exactly alike in construction and spaced from each other a distance equal to the thickness of the brace *b* and the portion *c* of the post. To this 15 end the plates are spaced from each other by spacing sleeves, and held in this spaced relation by means of transverse posts. As 20 illustrated, the plate 2 is formed with three bolt holes 11 extending approximately in line with the upper edge of the plate. Two more bolt holes are provided, designated 12, 25 one being disposed adjacent the lower edge of the plate and adjacent the curved portion 3, and the other is disposed intermediate the lower bolt hole and the upper edge of the plate. Spaced sleeves 13 are used to separate 30 the plates, as before stated, through these spacing sleeves, which are preferably three-fourths of an inch in diameter in a full sized mold, pass the half inch bolts 14. The reason for using half inch bolts in 35 three-fourths inch sleeves is to permit the bolts to be readily withdrawn so that there will be no necessity of hammering the bolts and thereby possibly breaking or marring the fence post.

40 Disposed between the plates are strips 15 and 16^a. The strip 16 rests upon the top of the concrete member *c* previously formed, while the strip 15 extends upward and inward at an inclination to the strip 45 16 so as to form one face of the brace *b*. In order to permit the strip 15 to be readily removed from its position immediately beneath the brace *b* and between the connecting portion *c* and the base portion *a*, I prefer- 50 ably form the strip in two sections, these sections having inclined abutting faces as at 17. By making the strip in two sections the strip will fall from its position as soon as the side pieces of the mold are removed from 55 engagement with the fence post and there will be no necessity of hammering the strip 15 out of its position. These strips 15 16 and 16^a are simply held in place by engagement with the walls of the mold, but the 60 strip 15 also rests upon the bolts passing through the bolt holes 11 so as to support the weight of the liquid concrete or grouting forming the brace *b*.

Inasmuch as liquid grouting or concrete is poured into the mold, it is necessary to

provide cover sections which will extend along and over the upper edges of the plates 2. There are two of these cover sections used, one being designated 18 and the other 19. Each of these sections is U-shaped transversely. The lower end of the section 18 is cut away to form a miter joint, while the upper end of the side flanges of the sections are longitudinally slotted as at 20. The side flanges of the section 19 at their lower ends are also longitudinally slotted as at 21, while the upper end of the section is mitered. When these sections are placed in position between the mold plates the ears 10 will enter the slots 20 and 21, the side flanges of the covering members 18 and 19 extending down over the upper margins of the plates 2, and these covering members will be held in position by transverse detachable strips 22 which are engageable in the slots 6 and 9, respectively.

The curved portions 3 of the mold plates are formed with a plurality of openings for the passage of transverse bolts, these openings in each plate being arranged in staggered relation. The perforations 23 are nearly one-half inch in diameter in the actual embodiment of my invention, and are for the purpose of forming openings through the fence post for permitting the attachment of the iron pipe or iron rod forming the end of the fence panel. The opening 24 is for a gate fastener, while the openings 25 disposed above and below the opening 24 are for the attachment of the gate hinges. These openings 24 and 25 are preferably nearly three-fourths of an inch in diameter. When the mold sections are arranged in proper relation to each other bolts 26 pass through the openings 23, 24 and 25, and surrounding these bolts are the sleeves 27, these sleeves being three-fourths of an inch in diameter for the openings 24 and 25, and preferably one-half inch in diameter for the openings 23. It will be noted that the bolts passing through the openings 23 are disposed at an angle to the bolts passing through the openings 24 and 25, so that these two sets of bolts cross each other.

With this form of mold, the lower portion of the fence post, that is, the portions a^x and c , are first formed as previously described, and preferably reinforced, the reinforcing rods of the portion a^x extending up from the ground. The mold sections are then assembled so that the curved portions 3 surrounding the reinforcing rods extend upward from the portion a^x and the mold is ready for use. The concrete or other composition in a relatively liquid state is now poured into the mold filling up the portion of the mold defined by the curved portions 3 and also filling up that portion of the mold between the strips 15 and the cover portions 18 and 120

125

130

19. After the concrete is set, which actual experience has shown me is in about twenty-four hours, the bolts holding the mold sections to each other are unloosened and removed. The covers 18 and 19 are taken off and the mold sections spread apart, and as before stated, the strip 15 will fall downward because it is made in two sections with the angular joint 17. The section 16 is relatively short and may be readily removed.

10 The form of mold shown in Fig. 10 is formed of precisely the same parts as that shown in Fig. 6, the only difference being that the plates are angular in plan so as to 15 form braces extending in two directions from the post. Thus the plate 2^x, which corresponds to the plate 2, is simply angular in cross section, while the plates 2^y, which 20 form the outer faces of the braces are connected by a circular portion 3^x through which passes the bolts which are designed to pass through the sleeves intended to be permanently formed in the post itself. Otherwise, the mold shown in Fig. 10 is precisely 25 the same as the mold shown in Fig. 6 and is supported in the same manner and used in the same way.

It will be seen that my invention is very simple, has very few parts, is cheaply made, 30 and that it is thoroughly effective in practice for the purpose intended.

Having described my invention, what I claim is:

1. In a mold for forming fence posts and 35 integral braces, oppositely disposed mold plates approximately triangular in form, a vertically disposed core member disposed between said plates to form a vertical channel to receive the material forming the post, 40 a downwardly inclined core member to form a downwardly inclined channel for the material forming the brace, said inclined channel opening at its upper end at the top corner of the mold, and cover sections disposed 45 on the downwardly inclined edges of the plates and extending over the downwardly inclined channel.

2. In a mold for forming fence posts and 50 integral braces, oppositely disposed mold plates formed to mold the exterior face of the post and brace, and a plurality of core strips detachably disposed between said mold plates and adapted to form the inner faces of the post and brace, said strips having 55 overlapped ends and one of said strips being made in two sections, the sections having inclined contacting faces whereby to permit the removal of the core strips from the completed post after the mold plates 60 have been detached and removed.

3. A mold for forming fence posts and 65 integral braces, comprising spaced mold plates triangular in form, said plates together being adapted to inclose the post to

laterally and downwardly extending integral brace, a core strip disposed between the plates and spaced below the downwardly inclined upper edges thereof, a vertically disposed core strip disposed between said plates 70 and extending downward from the upper end of the first-named core strip, and means for holding said plates connected with each other and holding the core strips in position.

4. A mold for forming fence posts and 75 integral braces, comprising spaced mold plates, together defining the fence post to be molded, said plates being triangular in form and having downwardly and outwardly inclined upper edges, a core strip disposed between the plates and below the inclined upper edges of the same, a vertically disposed core strip extending downward from the upper end of the first-named core strip, means 80 for holding said core strips in position and detachably connecting said plates, and means for covering the space between the upper edges of the plates.

5. A mold for forming fence posts and 85 integral braces, comprising spaced mold plates, together partially defining the fence post to be molded, said plates being triangular in form and having downwardly and outwardly inclined upper edges, a core strip disposed between the plates and below the 90 inclined upper edges of the same and defining the lower face of the integral brace, a vertical core strip disposed between the plates and extending downward from the upper end of the first-named core strip and 95 defining the inner face of the post, means for holding said core strips in position and detachably connecting said plates, means for covering the space between the upper edges of the plates, and means for holding said 100 covering means in place.

6. A mold for forming fence posts and 105 integral braces, including spaced mold plates, means for holding the plates in position, laterally extending lugs formed on the 110 mold plates, upwardly extending ears formed on the mold plates projecting beyond the edges of the plates, U-shaped covering plates adapted to embrace the edges of the plates and to have their side flanges inserted between said ears and the adjacent ends of the plates, said side flanges being longitudinally slotted to embrace said lugs, and transverse fasteners extending through the slots of the ears and over said covering 115 plates.

7. A mold for forming fence posts and 120 integral braces, including two spaced sections having outwardly projecting feet at their lower margins whereby the sections 125 may rest with their bases on the ground, said sections having downwardly and outwardly inclined upper edges, a sectional core strip disposed between the sections adjacent their inclined upper edges and extending down- 130

ward and outward, spacing sleeves disposed between the sections, certain of the sleeves supporting the core strip, bolts passing through said sleeves, covering members adapted to cover over the space between said sections and extend parallel to the outer face of the core strip, and means for holding said cover sections detachably in place.

8. A mold for forming corner fence posts and integral braces comprising an outer mold plate angular in plan having two integral wings, the two wings of the outer plate being connected by a curved web, the inner mold plate triangular in plan having two integral wings and spaced from the outer mold plate, both of said mold plates having their wings formed with down-

wardly and outwardly inclined upper edges, core strips disposed below but parallel to the upper edges of said mold plates and movably supported between the mold plates, vertical core strips disposed at the bases of each pair of wings and at their upper ends engaged with the first-named core strips, means for detachably holding the plates in spaced relation, and means carried by the mold plates for forming bushed passages through the fence post.

In testimony whereof I hereunto affix my signature in the presence of two witnesses. 30
MELVIN BURRIS.
